[57] CLAIM

The ornamental design for a convertible table, as shown and described.

DESCRIPTION

FIG. 1 is a perspective view of a convertible table in the folded condition embodying my design;
FIG. 2 is a perspective view of the convertible table of FIG. 1 with opposite sides elevated;
FIG. 3 is a perspective view of a modified embodiment in the closed position;
FIG. 4 is a perspective view of FIG. 3 with adjacent side panels elevated;
FIG. 5 is a perspective view of a further embodiment; and
FIG. 6 is a perspective view of FIG. 5 with all side panels elevated, with the illustrated view being slightly smaller than that shown in FIG. 5.

FIG. 1
